(57) CLAIM

The ornamental design for a roof for an agricultural work vehicle, substantially as shown and described.

DESCRIPTION

FIG. 1 is a perspective view of a roof for an agricultural work vehicle showing our new design, in which the phantom lines illustrate a portion of the agricultural work vehicle;

FIG. 2 is a top view thereof;

FIG. 3 is a right side view thereof;

FIG. 4 is a left side view thereof;

FIG. 5 is a front view thereof; and,

FIG. 6 is a back view thereof.

Phantom lining, where utilized, is for illustrative purposes only and forms no part of the claimed design.
